DESIGN FOR A COMPACT CASE

Carl H. Whitlock, Lockport, N. Y., assignor to Norton Laboratories, Lockport, N. Y., a corporation of Maine

Application May 14, 1935, Serial No. 56,828

Term of patent 7 years

To all whom it may concern:

Be it known that I, Carl H. Whitlock, a citizen of the United States, residing at Lockport, in the county of Niagara and State of New York, have invented a new, original, and ornamental Design for a Compact Case, of which the following is a specification, reference being had to the accompanying drawing, forming a part thereof.

Fig. 1 is a front view of a compact case showing my new design, and

Fig. 2 is a side view thereof.

I claim:

The ornamental design for a compact case
substantially as shown.

CARL H. WHITLOCK.
